INVENTOR:
RICHARD C. EVANS.
BY Whitley and Ruckman

ATTORNEYS.

UNITED STATES PATENT OFFICE.

RICHARD C. EVANS, OF ST. PAUL, MINNESOTA, ASSIGNOR OF ONE-HALF TO J. H. ERICKSON, OF MINNEAPOLIS, MINNESOTA.

WRENCH.

1,371,415.

Specification of Letters Patent. Patented Mar. 15, 1921.

Application filed January 12, 1920. Serial No. 351,019.

To all whom it may concern:

Be it known that I, RICHARD C. EVANS, a citizen of the United States, residing at St. Paul, in the county of Ramsey and State of Minnesota, have invented certain new and useful Improvements in Wrenches, of which the following is a specification.

My invention relates to wrenches, and particularly to wrenches having a fixed jaw and a slidable jaw. An object of my invention is to provide a slidable jaw which can be easily and readily moved by hand into contact with the object to be gripped by the wrench and which can then be tightened upon the object so as to prevent liability of the wrench slipping. Another object is to provide a wrench in which the act of turning the wrench causes the object to be so firmly gripped as to preclude slipping and damage to the corners or edges of the nut or other object which is engaged between the jaws of the wrench.

The full objects and advantages of my invention will appear in connection with the detailed description thereof, and the novel features embodied in my inventive idea will be particularly pointed out in the claims.

In the accompanying drawings which illustrate the application of my invention

is one form,

Figure 1 is a view in side elevation of my wrench. Fig. 2 is a view in side elevation in which a portion of the fixed jaw has been removed. Fig. 3 is a view in section on the line 3—3 of Fig. 2 looking in the direction of the arrow. Fig. 4 is a view in section on the line 4—4 of Fig. 2 looking in the direction of the arrow. Fig. 5 is a detail view showing the sliding jaw in released position.

As shown in the drawings, the fixed jaw of the wrench for convenience in manufacture consists of two members or parts 10 and 12, secured together by rivets 14, 16 and 18, the rivets 16 and 18 passing through extended portions of the fixed jaw members. A portion of the interior faces of the members 10 and 12 is removed so as to leave a cylindrical opening 20 and a space having flat walls 22 at the front of the opening 20, and also a space having flat walls 24 at the rear of the opening 20. A slidable jaw 26 is formed with a cylindrical portion 28 which is connected with the jaw proper by a reduced web portion 30. The cylindrical portion 28 is slidable in the opening 20 and the

web portion 30 is slidable in the space within the fixed jaw formed by the walls 22. A pin 32 on the side of the cylindrical portion 28 is slidable in a slot 34 formed in the member 12 of the fixed jaw. The rear of the cylindrical portion 28 is provided with ratchet teeth 36 and at the bottom of the space formed between the walls 24 is a projection 38 formed on its upper surface with a concave wall 40. The projection 38 closes a portion of the space at the bottom of the walls 24 and this projection may be formed integrally with the fixed jaw member 12, the rivet 18 passing through the projection and both of the extended portions of the fixed jaw. A handle member 42 is provided with an end portion 44 which is reduced in thickness so as to fit into the space formed between the walls 24, and part of this end is formed on the circumference of a circle whose center is at the center of a hole extending through the reduced end. The handle is pivotally attached by means of a bolt 46 passing through a hole in the jaw member 10 and the hole in the reduced portion 40, this bolt being screw-threaded into a screw-threaded hole in the jaw member 12. The end portion 44 is provided with a cylindrical transverse recess which rockably receives the cylindrical end 47 of a dog, the other end of which at 48 constitutes a detent for engagement with the ratchet teeth 36 when the handle 42 is moved about its pivot toward the position shown in Fig. 2. In order to hold the dog in engagement with the teeth 36, a coiled spring 50 has one end thereof inserted in a recess in the handle portion 44 and the other end of the spring encircles a projection 52 on the dog. When the handle is turned upwardly around its pivot upon the bolt 46, as shown in Fig. 5, the dog comes into engagement with the projection 38 and is moved against the tension of the spring 50 so that the slidable jaw is free and can be moved by hand within the limits permitted by the pin 32 working in the slot 34.

The operation and advantages of my invention will appear from the above description. When the dog 48 is in the position shown in Fig. 5, the fixed jaw is placed in contact with one side of the nut or other object to be turned and the slidable jaw is pushed by hand into contact with the other side of said object. Upon applying pres-

sure to the handle in the direction indicated by the arrow in Fig. 5, the dog is released and engages underneath one of the ratchet teeth 36. Upon continuing this pressure, 5 the slidable jaw is forced firmly into gripping engagement with the object so that the latter can be turned without liability of the wrench slipping. When the handle 42 comes into the position shown in Fig. 2, the 10 dog engages the closed portion above the walls 24 of the fixed jaw and the dog is locked in engagement with the ratchet teeth 36 as long as pressure in the direction indicated is continued. It is evident, therefore, 15 that the act of turning the wrench causes the object to be very firmly gripped by the jaws of the wrench. Upon exerting pressure upon the handle in the opposite direction, the dog is moved into the position 20 shown in Fig. 5 and the slidable jaw is released from its gripping engagement with the object.

I claim:

1. A wrench comprising a fixed jaw, a 25 handle member pivotally attached to said fixed jaw, a portion of the interior of said fixed jaw being removed to provide a cylindrical opening extending transversely with relation to said handle member and to provide flat walls at both the front and rear of said cylindrical opening, the forward end 30 of said handle member extending between said rear flat walls, a slidable jaw having a cylindrical guiding portion attached to its 35 main portion by a web portion, said cylindrical portion fitting slidably in said cylindrical opening and said web portion fitting slidably between said front flat walls, said cylindrical portion being provided on its 40 rear with ratchet teeth, a dog pivotally

mounted on the forward end of said handle member, a spring for normally holding said dog in engagement with said ratchet teeth, and means on said fixed jaw for retracting said dog when said handle member is turned 45 backwardly on its pivot.

2. A wrench comprising a two-part fixed jaw, means for securing said parts together, a handle member pivotally attached to said fixed jaw, a portion of the interior faces of 50 said parts of the fixed jaw being cut out to provide a cylindrical opening extending transversely with relation to said handle member, and to provide flat walls at both the front and rear of said cylindrical opening, 55 said handle member having a reduced forward end extending between said rear flat walls, a slidable jaw having a cylindrical guiding portion attached to its main portion by a web portion, said cylindrical portion 60 fitting slidably in said cylindrical opening and said web portion fitting slidably between said front flat walls, a pin on said cylindrical portion extending into a slot in said fixed jaw, said cylindrical portion being 65 provided on its rear with ratchet teeth, a dog pivotally mounted on the forward end of said handle member, a coiled spring having one of its ends mounted in a recess in 70 said handle member and its other end engaged with said dog for normally holding the latter in engagement with said ratchet teeth, and a projection on said fixed jaw for engaging and retracting said dog when said handle member is turned backwardly on its 75 pivot.

In testimony whereof I hereunto affix my signature.

RICHARD C. EVANS.
